United States Patent

Des. 241,409
Patented Sept. 14, 1976

241,409

GARDENING TOOL

Anton B. L. Lopizich, 3058 Capri Lane,
Costa Mesa, Calif. 92626

Filed Jan. 31, 1975, Ser. No. 545,824

Term of patent 14 years

Int. Cl. D8—01, 02

U.S. Cl. D8—6

FIG. 1 is a top front perspective view of a gardening tool, showing my new design;

FIG. 2 is a rear elevation thereof;

FIG. 3 is a right side elevation thereof;

FIG. 4 is a bottom plan view thereof;

FIG. 5 is a top front perspective view of a modified embodiment of the gardening tool illustrated in FIG. 1;

FIG. 6 is a rear elevation thereof;

FIG. 7 is a right side elevation thereof; and

FIG. 8 is a bottom plan view thereof.

I claim:

The ornamental design for a gardening tool, as shown and described.
